DESIGN FOR A LAWN MOWER FRAME

Herbert F. Dalglish, St. Paul, Minn.

Application July 22, 1946, Serial No. 131,800

Term of patent 14 years

(Cl. D40—1)

To all whom it may concern:

Be it known that I, Herbert F. Dalglish, a citizen of the United States, residing at St. Paul, county of Ramsey and State of Minnesota, have invented a new, original, and ornamental Design for a Lawn Mower Frame, of which the following is a specification, reference being had to the accompanying drawing, forming part thereof:

Figure 1 is a perspective view of a lawn mower frame, showing my new design;

Figure 2 is a top plan view of the same;

Figure 3 is a side elevational view showing the outer appearance of the same; and

Figure 4 is a sectional view showing the inner surface of the same.

I claim:

The ornamental design for a lawn mower frame, as shown.

HERBERT F. DALGLISH.
